UNITED STATES PATENT OFFICE.

CHARLES NETZEL, OF CHICAGO, ILLINOIS.

METALLIC BEDSTEAD.

No. 901,992.

Specification of Letters Patent. Patented Oct. 27, 1908.

Application filed March 2, 1908. Serial No. 418,862.

To all whom it may concern:

Be it known that I, CHARLES NETZEL, a citizen of the United States, residing at Chicago, in the county of Cook and State of Illinois, have invented a new and useful Improvement in Metallic Bedsteads, of which the following is a specification.

The object of my invention is to substitute for the fixed side bar sockets on the corner posts, and for the ordinary side bars in use; pivotal jaws attachable to the corner posts and reversible side and end bars whereby the several parts may be more cheaply made, more easily connected and better adjusted to support the movable parts on which the spring or mattress is placed.

The manner in which I accomplish my object is described in the following specification and illustrated in the accompanying drawings in which:

Figure 1 is a corner perspective elevation. Fig. 2 is a vertical section on the line 2—2. Fig. 1. Fig. 3 is a vertical section on the same line, the position of the side bar being the reverse of that shown in Fig. 2. Fig. 4 is a horizontal section on the line 4—4 Fig. 1. Fig. 5 is a perspective of the small part of the jaw disconnected. Fig. 6 is a perspective of the main part of the jaw, the side bar not being shown.

In the drawings A is one of the four corner posts which together with the rails affixed thereto form the head and foot parts of the bedsteads. In place of the side rail sockets which are permanently affixed to these posts, I provide a jaw indicated as a whole by the letter B. This jaw consists of two parts shown separately in Figs. 5 and 6. The main part of the jaw is indicated as 40 a whole by the letter C, and each part has a cylindrical portion D, which when the jaw is closed is adapted to encircle the post A. In the center of each of the portions D is a projection, D¹ adapted to enter a corresponding depression in the post as shown in Fig. 4, and thus to fix the position of the jaw on the post both vertically and horizontally.

In the body C is an aperture F shown in perspective in Fig. 6. Entering this aperture from the opposite side are channels X adapted to admit the end of an angle bar as hereinafter described, extending through this aperture F is a key way G. In the butt end H of the part C are two longitudinal parallel channels I. The face of J of the portion K between the channels I, is de-

pressed below the margin L of the channels I. Projecting from the face J is a lug M having a key way N. The other part of the jaw indicated as a whole by the letter O has a lip P, adapted to be inserted in the recess E in the part C, and is also provided with a lug Q and a key way therein said lug being adapted to enter the aperture F, and the key way R, to register with the key way G in the part C in position to receive and be locked by the key S as shown in Figs. 1 and 4.

Inserted in the channels I is a side angle bar T. Adjacent to the end of this bar is an aperture U adapted to admit the lug M and to be secured in place by the key V as shown in Figs. 1 and 2. By reversing the bar end for end the angular position of the bar is changed as shown in Fig. 3. At the head and at the foot of the bedstead, connected with the jaws is an angle bar W, corresponding in size and shape with the side bars T, the ends of these bars are provided with apertures adapted to register with the keyway G in the main part C of the jaw B, as shown in section in Fig. 4. When the end of the bar is inserted in the channels X, extending into the aperture F and these bars are secured by the key S which locks the jaws together. The reversal of these cross bars end for end change the angular position as described and illustrated in the side bars so the angle can be adjusted to correspond with either of the positions shown in section in Figs. 2 and 3.

What I claim and desire to secure by Letters Patent is:

1. In a bedstead, the combination with each corner post thereof; of a jaw adapted to grip said post and to support end and side bars, said jaw consisting of two members, one having a recessed lug, an aperture intersected by a keyway, channels adapted to receive the ends of cross bars, parallel channels adapted to receive the ends of side bars, a lug having a keyway located between said channels, the other member having a lip insertible in said recessed lug, and a lug insertible in said aperture, said lug having a keyway adapted to register with said intersecting keyway, a pair of cross bars supported in said jaws secured thereto by a key insertible in said intersecting keyway, and a pair of side bars supported in said parallel channels and secured therein by a key insertible in said keyway in said lug between said channels, said cross and side bars hav-

ing apertures adapted to admit therethrough said key, and keyway lug whereby said bars are made reversible as described.

2. In a bedstead of the kind described, the combination with each of the corner posts thereof; of an attachable and detachable jaw, each of said jaws consisting of two members, adapted to be joined and locked together on the post by a key insertible in 10 said members, each of said jaws having longitudinal and transverse channels adapted for the insertion and support therein of an angular cross bar and a side bar, said cross bar being locked to said jaw by a key 15 adapted to lock said jaw together on said post, and said side bar being locked to said jaw by a key insertible in said jaw as described.

3. A metallic bedstead jaw consisting of 20 two members, said members having a verti-

cal keyway and being locked together by a key inserted vertically in said keyway, one of said members having angular transverse channels intersecting said keyway, adapted for the insertion and support therein of either end of a perforated angular cross bar, and parallel longitudinal channels adapted for the insertion and support therein of either end of a perforated side bar and a keyway lug intermediate of said channels, 25 a key insertible, vertical in said members and cross bar thereby locking said members and cross bar together, and a key insertible in said lug thereby locking said member and said side bar.

CHARLES NETZEL.
